UNITED STATES PATENT OFFICE.

ALLISON M. MACFARLAND, OF BUFFALO, NEW YORK, ASSIGNOR TO KEYBOARD COM-
POSITOR CORPORATION, OF BUFFALO, NEW YORK, A CORPORATION OF NEW YORK.

TYPE SETTING AND DISTRIBUTING MACHINE.

1,206,451.

Specification of Letters Patent. Patented Nov. 28, 1916.

Application filed July 5, 1913. Serial No. 777,455.

To all whom it may concern:

Be it known that I, ALLISON M. MACFARLAND, a citizen of the United States, and resident of the city of Buffalo, in the county 5 of Erie and State of New York, have invented a certain new and useful Improvement in Type Setting and Distributing Machines, of which the following is a specification.

10 This invention relates to type setting and distributing machines which comprise upright magazines in which the type is contained in columns or stacks, and a keyboard by means of which the mechanisms are controlled by which the type is delivered from the magazines and conveyed to the assembling point or by which assembled type is distributed back to the magazines.

15 The objects of this invention are to produce a simple and efficient machine of this kind which is easily manipulated; in which the movable parts are comparatively light and can be operated at a high speed; which can be easily adjusted for assembling or 20 distributing type; which is particularly desirable for office use in setting type for duplicate letters, and which can be produced at comparatively small cost.

25 Briefly stated, the machine comprises a set of upright type magazines or containers in which the type is stacked in upright columns and from which the type is delivered at the bottom, one at a time, by an escapement mechanism. Further, the setting or assembling machine comprises a type collector or 30 assembling carrier which travels back and forth between the magazines and the point where the type is set or assembled and which carries each individual type from its 35 magazine to the assembling point; further, the distributing mechanism comprises a distributing carrier which receives the type, one at a time, from the bottom of the line or column of type which is to be distributed 40 and carries such type back to the appropriate magazine and deposits the type in the same; further, the machine comprises driving mechanism with which either the assembling carrier or the distributing carrier 45 can be connected at will for actuation; and further, the machine comprises a keyboard by which the movements of the parts are effected or controlled.

50 In the embodiment of the invention shown in the drawings, the magazines are

arranged in a circle about a common center and the type carriers travel to and from the magazines in a circular path, but it is not intended thereby to limit the invention to this arrangement since the magazines could 55 be arranged in a straight line or in any other manner if desired. The machine shown is also adapted to employ a particular kind of type generally used on printing machines adapted particularly for printing 60 circular or duplicate letters, which type is slotted at opposite faces to adapt it to enter a key hole slot on the type cylinder of a printing machine of this kind, but it will be understood that the machine can easily be 65 adapted to operate on other kinds of type.

70 In the accompanying drawings: Figure 1 is a sectional elevation of a type setting and distributing machine embodying the invention. Fig. 2 is a top plan view thereof. Fig. 75 3 is a fragmentary sectional plan, on an enlarged scale, in line 3—3, Fig. 1. Fig. 4 is a fragmentary sectional elevation on line 4—4, Fig. 2. Fig. 5 is a sectional plan on line 5—5, Fig. 1. Fig. 6 is a fragmentary 80 elevation of the machine, on an enlarged scale, showing some of the connections between the key levers and the stops for the movable type carriers. Fig. 7 is a fragmentary elevation, on a still larger scale, of a 85 part of the mechanism for shifting from capitals to small letters. Fig. 8 is a fragmentary perspective view of the mechanism for dropping type into a receptacle on a 90 type carrier. Fig. 9 is a fragmentary perspective view of the distributing mechanism showing the distributing type carrier in operative position over a type magazine. Fig. 10 is a top plan view thereof showing the distributing type carrier about to move 95 into its operative position. Fig. 11 is a fragmentary sectional plan view of the type collecting mechanism, on line 11—11, Fig. 1. Fig. 12 is a fragmentary sectional plan view thereof on line 12—12, Fig. 1. Fig. 13 is a fragmentary bottom plan view on line 13—13, Fig. 4. Fig. 14 is a fragmentary 100 elevation of some of the type magazines, partly in section, on line 14—14, Fig. 2. Fig. 15 is a fragmentary perspective view 105 of a type magazine, the means for releasing a type therefrom, and of the type collector in receiving position under the magazine. Fig. 16 is a fragmentary perspective view 110 showing the type collector in its type dis-

charging position. Fig. 17 is a fragmentary perspective view showing the means employed for operating a switch by means of the key levers. Fig. 18 shows diagrammatically the electrical connections between the various parts of the machine.

The frame of the machine may be constructed in any suitable manner, that shown in the drawings, Figs. 1 and 2, comprising 10 a base 20 having a rear wall 21 and side walls 22, and upright posts 23 which are fixed to the base and on which supporting rings 24, 25, 26 and 27 are secured. The posts 23 also support two cross bars 28 on 15 which the type carrying parts of the machine are mounted.

The actuating keys and key levers, by means of which the machine is operated, may, if desired, be mounted in the base. As 20 shown, keys 29 are secured on the front ends of key levers 30, which are pivoted at 31 to the rear wall 21 of the base.

The magazines in which the type is contained are arranged at the inner side of 25 the rings 24 and 26 and may be of any suitable construction adapted to contain the type for which the machine is used. The machine shown in the drawings is adapted to operate with type which has opposite slotted 30 faces and the magazines shown are constructed to coöperate with this kind of type. Each magazine consists of two guide strips 35, 35 which are so arranged as to form channels for the type and to engage in the 35 slots of the type 36, as shown in Figs. 2, 9, 11 and 14. These guides strips are secured to inwardly extending projections 37 formed on the supporting rings 24 and 26. The type is taken one at a time from the bottom 40 of the magazine channels by means of a type collector 40 and is placed into the upper open end of the magazine channels by means of a type distributor 41. Both of the type carriers are mounted on and adapted to rotate about the axis of a shaft or rod 42, journaled in the cross bars 28. Any suitable 45 means may be provided for moving these arms in opposite directions, those shown in the drawings being constructed as follows: 50 The type collector 40 is arranged between two clutch disks 43 and 44 which are revolvable in opposite directions, and the type distributor 41 is arranged between two similar clutch disks 45 and 46. The disks 43 and 55 45 are secured to the shaft 42, which is adapted to be driven in one direction by means of a pulley 47 secured thereto and a belt or other driving means, not shown. The disks 44 and 46 are secured on a sleeve 60 48 arranged on the shaft 42 and adapted to be driven in a direction opposite to that in which the shaft is driven by means of a pulley 49 secured to the sleeve. The type carriers 40 and 41 are made of magnetic material and each preferably consists of a cir-

cular portion which is located between the two oppositely revolving disks and which forms the armature of an electromagnetic clutch, and an outwardly extending arm which carries the type. In order to cause 70 the type carriers to turn with one or another of the disks, each disk is magnetizable at will in any suitable manner, for example, by means of magnets 50, mounted on the disk, two magnets being shown on each disk 75 in the construction illustrated. When the magnets of one disk are energized the type carrier adjacent thereto will be attracted to that disk and will revolve therewith. In the same manner if the magnets of the other 80 disk are energized the carrier will revolve therewith in the opposite direction. The energizing current is conducted to the magnets by means of a plurality of collector rings 51 and 52 secured respectively to the 85 sleeve 48 and the shaft 42, and the current is conducted to these rings by means of spring contacts 53 secured to stationary parts 54 of the machine, as shown in Fig. 3.

The magnets on the clutch disks are preferably connected with a source of current in such a manner that they can be actuated by the movement of any of the key levers. For this purpose the construction shown in Figs. 1, 2 and 17 may be employed, in which a bar 90 55 is so arranged underneath the key levers 30 as to be depressed when any of the key levers is depressed. This bar is connected to arms 56 extending outwardly from a switch actuating rod 57, pivoted in the base of the 100 machine. The switch actuating rod has a contact arm 58 mounted thereon which is adapted to engage with either one of two fixed contacts 59 and 60 for actuating the magnets of one or another of a pair of clutch 105 disks, as will be hereinafter more fully explained. It will be understood that only one pair of clutch disks is used at one time, the disks 43 and 44 being used when the machine is employed for setting up type, and 110 the other disks 45 and 46 being used when the type is distributed to the magazines. The actuating rod is normally held in position to cause the arm 58 to engage with the contact 59 by a spring 61 secured at one end 115 to a fixed part of the frame and at its other end to an arm 62 secured to the switch actuating rod 57.

Means are provided in operative relation to each of the magazines for stopping the 120 movement of the type collector when the same comes to a position in which it is adapted to receive type from the magazine, and for releasing the type from the magazine one at a time. In the construction 125 shown for this purpose, Figs. 1, 11, 12 and 13, a stop bar 63 is arranged adjacent to each of the magazines. This bar is pivoted at 66 intermediate of its ends on a rod 67, pivoted in the supporting rings 24 and 25 of 130

the frame of the machine. The outer end of the lever is connected to a link or wire 68 which is connected to one of the key levers 30, a spring 69 being interposed between the 5 key lever and the stop bar 65. The inner end of the stop bar is placed between two posts 70, which limit the swinging of the stop bar about a vertical axis. A spring 71 serves to normally hold the stop bar against 10 one of the posts. The end of the stop bar is arranged to enter the path of movement of the type collector when swung about its pivot 66, as shown in dotted lines in Fig. 15, by the depressing of the key lever with 15 which the stop bar is connected, and will stop the movement of the type collector so that type can be dropped from the magazine channel into a type receptacle 72 on the end of the collector. This type receptacle has a 20 vertical slot 73, which, when the type collector is stopped at one of the type magazines, will be in vertical alinement with the space between the two guide strips 35 of the type magazine, so that the type entering the 25 type receptacle will be held in the slot 73. A spring detent 74, secured to the collecting arm, has a portion which extends across the slot and prevents the type from falling through the slot until released.

30 The type is fed from the type magazines by means of an escapement mechanism actuated by the type collector. In the construction shown, see Figs. 1, 14 and 15, this mechanism consists of a type supporting bar 35 secured to the upright rod 67 and normally so positioned as to intercept the movement of the type through the magazine, and a spring detent 76, secured to the type supporting bar 75 and having its outer end 40 arranged at one side of the type in the magazine. When the type collector 40 engages the stop bar 65 it swings the rod 67 against the action of the spring 71 and thus moves the type supporting bar 75 from under the 45 column of type in the magazine and at the same time moves the detent 76 into engagement with the second lowest type in the column. This permits the lowest type to fall downwardly into the type receptacle 72.

50 When the movement of the type collector is reversed, the spring 71 returns the rod 67 to its normal position, placing the type supporting bar under the column of type in the magazine and moving the detent out of engagement with the type. This permits the 55 column of type in the magazine channel to drop on the type supporting arm, so that the escapement mechanism is ready to release another type. After a type has been dropped 60 into the type receptacle of the type collector, the collector is moved in the reverse direction until it strikes a stop 80, secured on the supporting ring 24. The type receptacle is then in a position vertically above a type 65 holder 81, Figs. 4 and 16, in which the type

is held prior to the placing of the same on the printing machine. The type holder 81 has a slot 82 for holding the type, which is in alinement with the slot 73 in the type receptacle 72 when the type collector is in this 70 position. As the type collector moves into this position, an extension 83 of the spring detent 74 engages with a bracket 84 secured to the supporting ring 24, thereby moving the spring detent away from the slot 73 in 75 the type receptacle, so that the type is released and drops through the slot 73 into the slot 82 of the type holder 81.

In the use of the machine to distribute the type back to the type magazines, a line of 80 type 90 to be distributed is placed in an upright column in an upright channel 91 forming a distributing magazine and having a slot 92 within which the type is confined. The type is fed one at a time from this support to the type distributor 41 by means of an escapement mechanism, Figs. 4 and 8, which comprises an upright rod 93 pivoted in the frame of the machine and which has a type supporting arm 94 which is normally in 85 vertical alinement with the line of type and prevents the same from passing downwardly in the slot 92, and a spring detent 95 adapted to engage with the second type from the bottom of the column. The rod 93 is swung 90 on its axis by means of a stop arm 96 secured to the rod 93 and adapted to be engaged by the type distributor to stop the movement of the arm so that a type receptacle 97 thereon and a slot 98 in the receptacle are in vertical alinement with the type distributing magazine 91 and the slot 92. The stop arm is arranged in a V-shaped slot 99 formed in the supporting ring 27, at the apex of which the rod 93 is pivoted. This 100 slot limits the movement of the stop arm and of the rod 93 in such a manner as to cause the type supporting arm 94 to swing from under the column of type 90 to release the lowest type and to move the spring detent 105 95 into engagement with the second type from the bottom of the column for preventing more than one type from dropping at one time. A spring 100 yieldingly holds the parts of the escapement mechanism in their 110 normal positions. The type is prevented from falling through the type receptacle 97 by means of a stop finger 101 mounted on a spring 102 secured on the type distributor 41, Figs. 8 and 9. The finger is yieldingly 115 held by the spring 102 in position to intercept the type in its passage through the slot 98 in the type receptacle 97.

The type distributor 41 is moved from its 120 initial position in the manner described, over the upper ends of the type magazines, and is caused to come to a stop over the desired type magazine by means of the following mechanism: Each of the stop bars 65 125 65 is connected by means of a link 105 to a 130

similar stop bar 106 arranged in operative relation to the upper end of the same type magazine with which the lower stop bar 65 co-operates. The stop bars 106, Figs. 1, 2 and 9, are pivoted on a wire 107 arranged on the upper supporting ring 27 so that the inner ends thereof can enter the path of movement of the type distributor and stop the same in position above the magazine. 16 The spring 102 to which the stop finger 101 is secured has an extension 109 which also engages with the stop bar 106 and swings the finger 101 out of engagement with the type in the receptacle 97 to drop into the type magazine. 15

In order to enable the same key lever to actuate two different characters, such as a capital and a small letter, suitable shift mechanism is employed. In the construction shown for this purpose, a shift ring 110 having a plurality of radial slots 111 is arranged on the supporting ring 26 of the machine in such a manner as to be slidable circumferentially through a limited space. 20 The slots 111 are so arranged as to permit one or another series of stop bars 106 to pass through the slots, depending upon whether the shift ring is in one or another position. The shift ring holds those stop bars against 25 moving into the path of movement of the type carrying member which do not pass through the slots 111. By means of the construction shown, only one shift ring is necessary for both the upper and lower stop bars 106 and 65, since, as is shown in Fig. 6, by holding one of the stop bars against movement, the other bar, being connected therewith by a rigid link, is also prevented from moving, so that the movement of the 30 key lever is taken up by the spring 69. The shift ring is guided in its movement by slots 112, through which the upright posts 23 of the frame of the machine pass.

Any suitable means may be employed for actuating the shift ring. In the construction shown for this purpose, the shift ring is connected to a bell crank lever 115 pivoted at 116 on the post 23 of the frame of the machine, by means of a pin 117 engaging in a slot in one arm of the lever. A spring 118 secured to the bell crank lever and a fixed part of the frame, normally holds the shift ring in one of its two operative positions. In order to shift the ring to its other 50 position, the other arm of the lever is connected through a link 119 or other suitable mechanism to shift levers 30, which can be depressed to shift the ring 110.

The shift ring shown is provided with one slot for every two type magazines, so that one key can actuate either one of two characters. By increasing the number of magazines and shifting the shift ring to a number of different positions, the machine can readily be adapted to enable each key to ac-

tuate a greater number of characters. For example, the machine could be constructed to operate on several different kinds of type.

The electrical connections between the various parts of the machine are shown diagrammatically in Fig. 18. 130 represents a battery or other suitable source of power for supplying current for energizing the magnets 50. One terminal of the battery is connected to a movable switch arm 131 which is adapted to engage with either of two contacts 132, 133, the switch arm being placed in engagement with the contact 132 to actuate the lower clutch member for using the machine for setting up type, and being placed in engagement with the contact 133 for actuating the upper clutch member for using the machine for distributing type. 70

The contact 132 is connected to a conductor 134 having two branches, one branch 85 135 conducting current to one of the lower contact rings 52 from where the current passes through the electromagnets 50 of the lower clutch disk 43 and thence to the other contact ring of the lower pair of rings and 90 by means of a conductor 136 to the contact 60 of the key-actuated switch. The other branch 137 of the conductor 134 connects one of the contact rings 51, which is connected with the magnets 50 of the clutch disk 44. The current passes from the magnets to another contact ring 51 and then through conductor 138 to the contact 59 of the key-actuated switch. Thus it will be seen that when any of the key levers is depressed, the movable contact member 58 is moved into engagement with the contact 60, which causes current to flow through the magnets of the clutch disk 43, so that the type collector 40 is moved to a type magazine. When the key lever is released, the contact member 58 is moved back into engagement with the contact 59 by the spring 61, thus causing the magnets of the clutch disk 44 to be actuated and carrying the type collector 40 back to its normal position over the type holder 81. The other switch contact 133 is connected to a conductor 140, which has two branches 141 and 142. The branch 141 is connected through one of the contact rings 51 to the magnets 50 of the clutch disk 45 and thence through another of the contact rings 51 and conductor 138 to contact 59 of the key-actuated switch. The other branch 142 of the conductor 140 connects with one of the upper pair of contact rings 52, from which the current is conducted to the magnets 50 of the clutch disk 46 and back through the other contact ring 52 through a conductor 143 to the contact 60. The actuation of the upper clutch disks from the key levers when the switch arm 131 engages the contact 133 to operate the type distributing member 141 is similar to the operation of the lower clutch 105 110 115 120 125 130

disks above explained. Any other suitable electrical connections for causing the actuation of the type carriers 40 and 41 as described may be employed.

5 The machine has the advantage over other machines of this kind as heretofore constructed that the type carriers are of light construction and only carry one type at a time, so that they do not require much momentum when in motion and can be moved and stopped quickly. The magnetized clutch disks prevent any rebound after a member strikes a stop bar. The machine can therefore be operated at a much higher speed

10 than other machines heretofore made.

15 The machine can be used either for setting up or distributing type, and to change from one use to the other it is only necessary to move the switch member 131 from one of the contacts 132 or 133 to the other. The keyboard of the machine can be arranged like the keyboard of an ordinary typewriter, so that the machine can be operated by any person accustomed to operating a typewriter.

20 I claim as my invention:

25 1. In a type setting machine, the combination with a plurality of stationary type magazine channels and a stationary holder adapted to receive type, of a type carrier adapted to be moved into operative relation with reference to any of said magazine channels for receiving type therefrom and to carry the type so received to said holder, and means actuated by the carrier when the same is in position to receive type from a magazine for discharging type from said magazine channels to said carrier.

30 2. In a type setting machine, the combination with a plurality of stationary type magazine channels and a stationary holder adapted to receive type, of a type carrier adapted to be moved into operative relation with reference to any of said magazine channels for receiving type therefrom and to carry the type so received to said holder, and means actuated by the carrier when the same is in position to deposit type into said holder for discharging type from said carrier into said holder.

35 3. In a type setting machine, the combination with a plurality of stationary type magazine channels and a stationary holder adapted to receive type, of a type carrier adapted to be moved into operative relation with reference to any of said magazine channels for receiving type therefrom and to carry the type so received to said holder, means actuated by the carrier when in operative position to receive type from a magazine for discharging type from said magazine channels to said carrier, and means for discharging type from said carrier into said holder.

40 4. In a type setting machine, the combi-

nation with a plurality of stationary type magazine channels, of a stationary type holder, a movable type carrier, means for stopping said carrier at any of said magazine channels, and means actuated by the engagement of said carrier and said stop means for dropping type from a magazine channel into said carrier when the same is so stopped.

45 5. In a type setting machine, the combination with a plurality of stationary type magazine channels, of a stationary type holder, a movable type carrier, means for stopping said carrier at any of said magazine channels, means for dropping type from a magazine channel into said carrier, and means for stopping the carrier at said holder and releasing the type from the carrier to deposit the type in said holder.

50 6. In a type setting machine, the combination with a plurality of stationary type magazine channels, a stationary type holder adapted to receive type, a type carrier, frictional means for moving the carrier into and holding the same in operative relation to a magazine to receive a type, and frictional means for moving the carrier to the holder to place the type so received therein.

55 7. The combination with a stationary type magazine channel, of a type carrier movable toward and from said magazine channel, and means adapted to be engaged by said carrier for stopping the movement of the carrier and which are actuated by the movement of the carrier to feed type from the magazine to the carrier.

60 8. The combination with a stationary type magazine channel, of a type carrier movable toward and from said channel, and means adapted to be engaged by the carrier and actuated by the movement of the carrier to drop a type from the magazine channel into the carrier.

65 9. The combination with a stationary type magazine channel, of a type carrier movable toward and from said channel, and means adapted to be inserted into the path of movement of the carrier and to be engaged by the carrier and actuated by the movement of the carrier to drop a type from the magazine channel into the carrier.

70 10. The combination with a stationary type magazine channel, of a type carrier movable toward and from said channel, a part adapted to be inserted into the path of movement of the carrier and to be engaged by the carrier and actuated by the movement of the carrier to release type from said magazine channel, and a key for actuating said part.

75 11. The combination with a stationary type magazine channel, of a type carrier movable toward and from said channel, a part adapted to be inserted into the path of movement of the carrier and to be engaged

by the carrier and actuated by the movement of the carrier to release type from said magazine channel, and key-actuated means for actuating said carrier and for placing 5 said part into the path of movement of the carrier.

12. The combination with a plurality of stationary type magazine channels, of a type carrier movable toward and from said channels, a type releasing member for each channel, said member having a part adapted to be inserted into the path of movement of the carrier and actuated by impact with the carrier to place type into said carrier, 15 a key for each releasing member adapted to place said part of the type releasing member into the path of the carrier, and means actuated by any of said keys for actuating the carrier.

20 13. The combination with a stationary type magazine channel, of a type carrier movable toward and from said channel in a direction crosswise with regard to the channel, an escapement mechanism for releasing type from said magazine channel, and a part on said escapement mechanism adapted to be placed in a position to be engaged by the carrier while moving in said crosswise direction for actuating the escapement mechanism to drop a type.

14. In a type setting machine, the combination with a plurality of stationary type magazine channels, of a type carrier movable toward and from said magazine channels, a key lever, means actuated by said key lever for moving said carrier, means actuated by said key lever for stopping the carrier in operative relation to a type magazine channel, and means actuated by said stop means for feeding type from said channel to said carrier.

15. In a type setting machine, the combination with a plurality of stationary type magazine channels, of a type carrier movable toward and from said channels, means for stopping the carrier in operative relation to the type magazine channels, key levers for actuating said stop means, and means actuated by the engagement of said carrier with said stop means for feeding type from said channels to said carrier.

16. In a type setting machine, the combination with a plurality of stationary type magazine channels, of a type carrier movable toward and from said channels, means operatively arranged with regard to each channel and adapted to be actuated to stop the movement of the type carrier in operative relation thereto, key levers operatively connected with said stop means, and means actuated by said stop means for feeding type from said channels to said carrier.

17. The combination with a stationary type magazine channel, of a movable type carrier, escapement mechanism for control-

ling the delivery of type from the magazine channel, and means on said escapement mechanism adapted to be engaged by said carrier in its movement into operative relation to the magazine channel for actuating 70 the escapement mechanism to drop a type into said carrier when the same is in operative relation to the magazine channel.

18. The combination with a stationary type magazine channel, of a movable type carrier, escapement mechanism for controlling the delivery of type from the magazine channel, and means actuated by the carrier in its movement into operative relation to a magazine channel for causing the escapement to drop a type into said carrier when the same is in operative relation to the magazine channel.

19. The combination with a stationary type magazine channel, of a type carrier movable substantially transversely of said channel, and escapement mechanism for controlling the delivery of type from the magazine channel and having a part adapted to be inserted into the path of movement of said carrier, said escapement being actuated by the engagement of said part with said carrier while said carrier is moving in said transverse direction.

20. The combination with a stationary type magazine channel, of a movable type carrier, escapement mechanism for controlling the delivery of the type from the magazine channel to said carrier, and a stop member operatively connected with said escapement mechanism and adapted to be inserted into the path of movement of said carrier for stopping the movement thereof, said escapement mechanism being actuated by the striking of the stop member by said carrier.

21. The combination with a stationary type magazine channel, of a movable type carrier, escapement mechanism for controlling the delivery of the type from the magazine channel to said carrier, a stop member operatively connected with said escapement mechanism and adapted to stop said carrier in operative relation to a magazine channel and to actuate said escapement mechanism when struck by said carrier, and a key for actuating said stop.

22. The combination with a stationary type magazine channel, of a movable type carrier, escapement mechanism controlling the delivery of type from said channel, a stop bar, a key lever connected with said stop bar for moving the same into the path of movement of the type carrier, and means controlled by the striking of the stop bar by said carrier for actuating said escapement mechanism.

23. The combination with a stationary type magazine channel, of a movable type carrier, escapement mechanism controlling the delivery of type from the channel, a

stop bar, a key lever connected with said stop bar for moving the same into the path of movement of the type carrier, means operated by said key lever for moving said carrier, and means controlled by the striking of the stop bar by said carrier for actuating said escapement mechanism.

24. The combination with a stationary type magazine channel, of a type carrier movable toward and from said channel, escapement mechanism for controlling the delivery of type from the channel to said carrier, said mechanism comprising an arm on which the type is adapted to rest, a detent 15 adapted to engage the second type from the bottom of the channel, and a stop bar with which said carrier is adapted to engage and which is operatively connected with said arm and said detent to move said arm from 20 under said channel and said detent into engagement with the second type from the bottom of the channel when engaged by said carrier.

25. In a type setting machine, the combination with a plurality of stationary type magazine channels, of a stationary type holder, a type carrier adapted to move into operative relation to said magazine channels and said holder, a type receptacle on said 30 carrier adapted to receive type from said magazines, and means actuated by the movement of said carrier toward said holder for discharging the type from said receptacle into said holder.

35 26. In a type setting machine, the combination with a plurality of stationary type magazine channels, of a stationary type holder, a type carrier adapted to move into operative relation to said magazine channels 40 and said holder, a type receptacle on said carrier adapted to receive type from said channels and having a slot in which said type is contained, means mounted on said carrier for holding the type from passing 45 through said slot, and means for releasing the type to discharge the same from said receptacle to said holder.

27. In a type setting machine, the combination with a plurality of stationary type 50 magazine channels, of a stationary type holder, a type carrier adapted to move into operative relation to said channels and said holder, a type receptacle on said carrier adapted to receive type from said channels 55 and having a slot in which said type is contained, a spring detent for holding the type from passing through said slot, and a fixed part which engages said detent when the carrier moves into operative relation with 60 the holder for moving the detent to release the type and discharge the same from the receptacle to the holder.

28. In a type setting machine, the combination with keys, of a single type collector, 65 a series of type magazine channels, a holder

for the assembled type, a source of power, and means actuated by the operation of a selected key on the keyboard which cause said source of power to move the type collector to and from a corresponding type 70 holder to receive a type.

29. In a type setting machine, the combination with keys, of a plurality of vertical type magazine channels, one for each character, a type collector arranged to travel 75 beneath the magazines, a type distributor arranged to travel above the magazines, a source of power, and means connected with said keys for causing said source of power to operate the collector and distributor. 80

30. In a type distributing machine, the combination with a plurality of stationary type magazine channels having open upper ends, of a stationary distributing magazine for a column of type to be distributed, a 85 movable type carrier adapted to carry type from said distributing magazine to the open upper ends of said magazine channels, means for stopping the carrier in operative relation to a magazine channel, and means 90 actuated by said stop means for releasing the type from the carrier.

31. In a type distributing machine, the combination with a plurality of stationary type magazine channels having open upper 95 ends, of a distributing magazine for a column of type to be distributed, a movable type carrier adapted to carry type from said distributing magazine to the open upper ends of said magazine channels, means for 100 stopping the carrier in operative relation to said distributing magazine, means actuated by said stop means for discharging type from said magazine into said carrier, and means for discharging type from the 105 carrier into a magazine channel.

32. In a type distributing machine, the combination with a plurality of stationary type magazine channels having open upper ends, of a distributing magazine for a column of type to be distributed, a movable type carrier, means for discharging type from said distributing magazine to said carrier, means for stopping said carrier over any of said magazine channels, and means 115 actuated by said stop means for dropping type from the carrier into the open upper end of the magazine channel.

33. In a type distributing machine, the combination with a plurality of stationary 120 type magazine channels having open upper ends, of a distributing magazine for a column of type to be distributed, an escapement mechanism for discharging the type from said distributing magazine, a type carrier into which the type is dropped by said escapement mechanism and which carries the type to said magazine channels and means for stopping the carrier in operative 125 relation to the distributing magazine, said 130

escapement being actuated by the engagement of said carrier with said stop means.

34. In a type distributing machine, the combination with a plurality of stationary type magazine channels having open upper ends, of a distributing magazine for a column of type to be distributed, a movable type carrier, a type receptacle on said carrier, means for stopping said carrier in operative relation to said distributing magazine, means for dropping type from said distributing magazine into said receptacle, means for releasably holding the type in said receptacle and adapted to be actuated by engagement with said stop means for releasing the type when said receptacle is over a magazine channel to drop the type into the open upper end of said magazine channel.

35. In a type distributing machine, the combination with a plurality of stationary type magazine channels having open upper ends, of a distributing magazine for a column of type to be distributed, a movable type receptacle having a slot in which the type is confined, means for dropping type from said distributing magazine into said receptacle, a stop for intercepting the passage of said type through said slot, and means in the path of movement of the receptacle for removing the stop from the path of movement of the type to permit the type to be discharged from said type receptacle to a magazine channel.

36. In a type distributing machine, the combination with a plurality of stationary type magazine channels having open upper ends, of a distributing magazine for a column of type to be distributed, a movable type carrier, means adapted to frictionally engage the carrier for moving the same to said distributing magazine to receive a type, and frictional means for moving the carrier to a magazine channel to place the type therein, said frictional means serving to hold the carrier in either of its positions.

37. In a type distributing machine, the combination with a plurality of stationary type magazine channels having open upper ends, of a distributing magazine for a column of type to be distributed, a movable type carrier adapted to move back and forth between said distributing magazine and the magazine channels, key levers for the magazine channels, and means frictionally engaging said carrier for moving the same to a magazine channel when a key lever is depressed and for holding the same in said position.

38. In a type setting and distributing machine, the combination with a plurality of keys, a series of stationary type magazine channels, an escapement for each magazine channel, a movable type collector, a movable type distributer, and means for

connecting said keys with either said collector or said distributer for actuating either said collector or said distributer when any one of the keys is actuated.

39. In a type distributing machine, the combination with a plurality of stationary type magazine channels having open upper ends, of a distributing magazine for a column of type to be distributed, a movable type carrier adapted to carry type from said distributing magazine to said magazine channels, and a stop bar for each magazine channel which is adapted to be actuated to stop the carrier in operative relation to the magazine channel and to release the type contained in the carrier and drop the same into the open upper end of said magazine channel.

40. In a type distributing machine, the combination with a plurality of stationary type magazine channels having open upper ends, of a distributing magazine for a column of type to be distributed arranged with its lower end above the level of said open upper ends of said magazine channels, and a type carrier movable in a path between the upper ends of the magazine channels and the lower end of said distributing magazine and adapted to receive type from said distributing magazine to drop the type into the open upper ends of said magazine channels.

41. In a type distributing machine, the combination with a plurality of stationary type magazine channels having open upper ends, of a distributing magazine for a column of type to be distributed arranged with its lower end above the level of said open upper ends of said magazine channels, a type carrier movable in a path between the upper ends of the magazine channels and the lower end of said distributing magazine and adapted to receive type from said distributing magazine to drop the type into the open upper ends of said magazine channels, and a stop bar for each magazine channel which is adapted to be actuated to stop the carrier in operative relation to the magazine channel and to release the type contained in the carrier.

42. In a type distributing machine, the combination with a plurality of stationary type magazine channels having open upper ends, of a distributing magazine for a column of type to be distributed arranged with its lower end above the level of said open upper ends of said magazine channels, a type carrier movable in a path between the upper ends of the magazine channels and the lower end of said distributing magazine and adapted to receive type from said distributing magazine to drop the type into the open upper ends of said magazine channels, a stop bar for each magazine channel which is adapted to be actuated to

stop the carrier in operative relation to the magazine channel and to release the type contained in the carrier, key levers for actuating said stop bars, and means actuated by the depressing of any of said key levers to move said carrier.

43. The combination with a stationary type magazine channel having an open upper end, of a type carrier movable above said channel toward and from the same, and means adapted to be inserted into the path of movement of the carrier for stopping the carrier in operative relation to a magazine channel and for causing the carrier to release a type and drop the same into said magazine channel.

44. The combination with a stationary type magazine channel, of a type carrier movable toward and from said channel, a holder on said carrier for receiving the type, and means adapted to be engaged by the carrier for actuating said holder to release the type.

45. In a type distributing machine, the combination of a magazine containing the type to be distributed, a plurality of magazine channels adapted to receive the type, a movable type distributor adapted to carry type from said distributing magazine to said channels, means on said distributing magazine adapted to be actuated by said distributor to feed type to said distributor, and means adjacent to said magazine channels adapted to engage said distributor for releasing the type held in said distributor.

46. In a type setting machine, the combination of a plurality of type magazine channels, a holder for the type, a movable type collector adapted to carry type from said channels to said holder, means on said magazine channels adapted to be actuated by said collector to feed type to the collector, and means adjacent to said holder and adapted to engage said collector for releasing the type held in said collector.

47. In a type setting and distributing machine, the combination with a plurality of stationary type magazine channels, of a movable type carrier adapted to collect type from said channels, a movable type carrier adapted to distribute type to said channels, stop members for each magazine channel adapted to enter the path of movement of the carriers, and key levers adapted to actuate the stop members to stop the carriers, the stop members of one channel being both connected to the same key lever.

48. The combination with a plurality of stationary type magazine channels, of a type carrier movable to and from said magazine channels, a stop member for each channel adapted to be actuated to stop the carrier in operative relation to said channel, key levers adapted to actuate said stop members, each key lever being operatively connected with a group of stop members,

connected with a group of stop members, and means for preventing a key lever from actuating more than one stop member of a group at one time.

49. The combination with a plurality of stationary type magazine channels, of a type carrier movable to and from said channels, a stop member for each channel adapted to be moved into the path of movement of the carrier to stop the same in operative relation to a channel, key levers adapted to actuate said stop members, each key lever being operatively connected with a group of stop members, and means for holding all but one of the stop members of a group against movement at one time.

50. The combination with a plurality of stationary type magazine channels, of a type carrier movable to and from said channels, a stop member for each channel adapted to be moved into the path of movement of the carrier to stop the same in operative relation to a channel, key levers adapted to actuate said stop members, each key lever being operatively connected with a group of stop members, a slotted member having a slot for each key lever through which one of the stop members of a group is adapted to pass, and means for shifting said slotted member to permit another stop member of the group to pass through said slot.

51. The combination with a plurality of stationary type magazine channels, of a type carrier movable to and from said channels, a stop member for each channel adapted to be moved into the path of movement of the carrier to stop the same in operative relation to a channel, key levers adapted to actuate said stop members, each key lever being operatively connected with a group of stop members, a slotted member having a slot for each key lever through which one of the stop members of a group is adapted to pass, means for shifting said slotted member to permit another stop member of the group to pass through said slot, a shift key, and mechanism connecting said shift key with said shift member for placing the slots therein in register with different stop members.

52. The combination with a plurality of stationary type magazine channels, of a type carrier movable to and from said channels, a stop member for each channel adapted to be actuated to stop the carrier in operative relation to said channels, key levers adapted to actuate said stop members, each key lever being operatively connected with a group of stop members, means for preventing a key lever from actuating more than one stop member of a group at one time, and means operated by the key levers for actuating the carrier.

53. In a type setting and distributing machine, the combination with a plurality

of stationary type magazine channels, of a type collector adapted to collect type from the channels, a type distributer adapted to distribute type to the channels, stop members for each channel adapted to be moved into the path of movement of the type collector and distributer, key levers adapted to actuate the stop members of a plurality of channels, and means for preventing a key lever from actuating the stop members of more than one channel at one time.

54. In a type setting and distributing machine, the combination with a plurality of stationary type magazine channels, of a type collector adapted to collect type from the channels, a type distributer adapted to distribute type to the channels, stop members for each channel adapted to be moved into the path of movement of the type collector and distributer, key levers adapted to actuate the stop members of a plurality of channels, and means coöperating with one of the stops of each channel for preventing a key lever from actuating the stop members of more than one channel at one time.

55. In a type setting and distributing machine, the combination with a plurality of stationary type magazine channels, of a type collector adapted to collect type from the channels, a type distributer adapted to distribute type to the channels, a series of stop members adapted to intercept the movement of the collector, a series of stop members adapted to intercept the movement of the distributer, key levers adapted to actuate the stop members of a plurality of channels, a slotted member having a slot for each key lever through which one of the stop members is adapted to pass at a time, said slotted member coöperating with only one of said series of stop members, means connecting the two stop members of each channel, and means for shifting the slotted member to place the slots in operative relation to other stop members.

56. In a type setting machine, the combination with a plurality of stationary type magazine channels arranged in the circumference of a circle, of a stationary type holder arranged in said circumference, a type carrier movable about the center of said circle, means for stopping the carrier at any of said magazine channels, and means actuated by the engagement of said stop means by said carrier for feeding type from a channel into said carrier when the same is stopped in operative relation to the channel.

60. 57. In a type setting machine, the combination with a plurality of stationary type magazine channels arranged in the circumference of a circle, of a shaft arranged centrally in said circle, a type carrier movable about said shaft, and a clutch mounted on

said shaft and adapted to frictionally engage said type carrier for moving the same to and from said channels to receive type and for holding the carrier against rebound when stopped.

58. In a type setting machine, the combination with a plurality of stationary type magazine channels arranged in the circumference of a circle, of a shaft arranged centrally in said circle, a type carrier movable about said shaft, a clutch mounted on said shaft and adapted to frictionally engage said type carrier for moving the same to and from said magazine channels to receive type and for holding the same against rebound when stopped in operative relation to said channels, key levers for the magazine channels, and means operated by the key levers for actuating said clutch.

59. In a type setting machine, the combination with a plurality of stationary type magazine channels arranged in the circumference of a circle, of a type carrier adapted to move about the center of said circle, a stop member for each channel adapted to intercept the movement of the carrier, key levers for the channels, and means actuated by said key levers for placing a stop member in position to intercept the carrier, the engagement of said carrier with a stop member causing the release of a type from the corresponding magazine channel.

60. In a type setting machine, the combination with a plurality of stationary type magazine channels arranged in the circumference of a circle, of a type carrier adapted to move about the center of said circle, a stop member for each magazine channel adapted to intercept the movement of the carrier, key levers for the channels, means actuated by said key levers for placing a stop member in position to intercept the carrier, and release the type therefrom, a source of power, and means operated by said levers for causing said source of power to move said carrier.

61. In a type setting machine, the combination with a plurality of stationary type magazine channels, of a type carrier adapted to move to and from said magazine channels, clutches for operating said carrier, a stop member for each channel adapted to intercept the movement of the carrier, key levers for the channels, means actuated by the key levers for placing a stop member in position to stop the carrier independently of said clutches, and means operated by the key levers for actuating said clutches.

62. In a type setting machine, the combination with a plurality of stationary type magazine channels, of a type carrier movable to and from the magazine channels, means for stopping said carrier in operative relation to a magazine channel, key levers for actuating said stop means, an electro-

magnetic clutch adapted to actuate said carrier, and electrical connections for actuating said clutch when any one of said key levers is depressed.

- 5 63. In a type setting and distributing machine, the combination with a plurality of upright stationary type magazine channels arranged in the circumference of a circle and having open upper ends, of a type collector movable about the center of said circle and adapted to receive type from the lower ends of said channels, a distributing magazine arranged above said magazine channels, a type distributor movable about said center 10 and adapted to carry type from said distributing magazine to the upper ends of said channels and a key-board for controlling the operation of said collector and distributor.

64. The combination with a stationary type magazine channel, a type carrier movable toward and from said channel, a movable actuating member yieldingly connected with said carrier, and means for stopping said carrier while said actuating member 25 continues its movement.

65. The combination with a stationary type magazine channel, a type carrier movable toward and from said channel, an actuating member for said type carrier, means for yieldingly connecting said carrier with said actuating member, and means for stopping the movement of said type carrier while said actuating member continues its movement.

35 66. The combination with a stationary type magazine channel, a type carrier movable toward and from said channel, a continuously moving actuating member frictionally connected with said carrier for moving the same, and means for stopping said carrier without stopping said actuating member.

67. The combination with a stationary type magazine channel, a type carrier movable toward and from said channel, a continuously movable actuating member for moving the carrier to said magazine channel, a continuously movable actuating member for moving the carrier from said magazine channel, and means for operatively connecting said carrier with either of said actuating members.

55 68. The combination with a stationary type magazine channel, a type carrier movable toward and from said channel, a continuously moving actuating member adapted to be yieldingly connected with said carrier, a key, and means operated by the key for stopping said carrier without stopping said actuating member.

69. The combination with a stationary type magazine channel, a type carrier movable toward and from said channel, a continuously moving actuating member adapted to be frictionally connected with said

carrier for moving the same, a key, means actuated by said key for causing said actuating member to engage said carrier, and means actuated by said key for stopping said carrier without stopping said actuating member.

70. The combination with a plurality of stationary type magazine channels, of a movable type carrier adapted to receive type from the channels, and a friction clutch 75 adapted to yieldingly engage the type carrier for moving the same into operative position to said channels and to hold the same in said position against rebound.

71. In a type setting machine, the combination with a plurality of stationary type magazine channels, of a type carrier movable to and from said magazine channels and adapted to receive type from a magazine channel, means for stopping the movement of the carrier in operative relation to a magazine channel, and a friction clutch adapted to yieldingly engage the carrier for moving the same and to hold the same 80 against rebounding from said stopping 85 means.

72. The combination with a plurality of stationary type magazine channels, of a type carrier movable toward and from said magazine channels, a clutch for moving 95 said carrier in opposite directions, said clutch comprising oppositely disposed disks revolving in opposite directions, and means for actuating the carrier from either of said disks.

73. The combination with a plurality of stationary type magazine channels, of a type carrier movable toward and from said magazine channels, a clutch for moving said carrier in opposite directions, said clutch 100 comprising oppositely disposed disks revolving in opposite directions and either of which is adapted to be magnetized to actuate said carrier.

74. The combination with a plurality of stationary type magazine channels arranged in the circumference of a circle, of a type carrier movable about said center into and out of operative relation to the channels, a clutch for moving said type carrier in opposite directions, said clutch comprising disks arranged at opposite sides of the carrier and revolving in opposite directions, and means for moving the carrier into engagement with either of said disks.

110 75. The combination with a plurality of stationary type magazine channels arranged in the circumference of a circle, of a type carrier movable about said center into and out of operative relation to the channels, a clutch for moving said type carrier in opposite directions, said clutch comprising disks arranged at opposite sides of the carrier and revolving in opposite directions, and means for magnetizing either of said 115 120 125 130

clutch disks to draw the carrier into operative engagement therewith.

76. The combination with a plurality of stationary type magazine channels arranged in the circumference of a circle, of a central shaft rotating in one direction, a surrounding sleeve rotating in the opposite direction, clutch disks secured respectively to said sleeve and said shaft, a carrier arranged between said disks and adapted to be moved into and out of operative relation to said channels, and means for causing said carrier to engage with either of said disks.

77. The combination with a plurality of stationary type magazine channels arranged in the circumference of a circle, of a central shaft rotating in one direction, a surrounding sleeve rotating in the opposite direction, clutch disks secured respectively to said sleeve and said shaft, a type collecting carrier arranged between said disks and adapted to be moved into operative relation to said channels to receive type, a second pair of clutch disks on said shaft and sleeve, a type distributing carrier arranged between said second pair of clutch disks and adapted to be moved into operative relation to the type magazine channels to discharge type into the same, an electric circuit including means for magnetizing any one of said clutch disks, and a switch adapted to connect either one of said pairs of clutch disks to the circuit.

78. In a type setting and distributing machine, the combination of a distributing magazine for a column of type to be distributed, a type distributor, an escapement controlling the delivery of type from said magazine to the distributor, and a stop for the distributor carried by the escapement.

79. In a type setting and distributing machine, the combination of a distributing magazine for a column of type to be distributed, a type distributor, an escapement controlling the delivery of type from said magazine to the distributor, means carried by the escapement for stopping the distributor, and means whereby the engagement of said stop means by the distributor operates the escapement and causes a type to be delivered to the distributor.

80. In a type setting and distributing machine, the combination of a distributing magazine for a column of type to be distributed, a series of type magazine channels one for each character desired, a distributor adapted to distribute the type from said distributing magazine to the type magazine channels, an escapement controlling the delivery of type from the distributing magazine to the distributor, a stop member operatively connected with the escapement and arranged both to stop the distributor and operate the escapement, and

keyboard controlled means for operating the distributor.

81. In a machine for setting and distributing type, the combination with keys and a plurality of type magazine channels adapted to hold type in columns, of a type carrier, means for operating the type carrier, a series of stops, one for each type magazine channel, each stop being controlled by a key in such a way that the act of pressing the key will cause the stop connected therewith to intersect the path of the carrier and stop said carrier in position to receive a type from the magazine channel located adjacent to said stop, and means whereby the engagement of the stops by the carrier will cause type to be delivered to the carrier.

82. In a type setting and distributing machine, the combination of a plurality of keys, a series of stationary magazine channels, a type collector adapted to receive type from said magazine channels, a type distributor adapted to place type into said magazine channels, electrical circuits adapted to be completed by any of said keys for actuating said collector and said distributor, and a switch for connecting said circuits so as to actuate either said collector or said distributor when a key is operated.

83. In a type setting and distributing machine, the combination of a plurality of substantially upright magazine channels, a magazine for the type to be distributed arranged above the upper ends of said magazine channels, a type distributor for carrying type from the distributing magazine to the magazine channels and movable in a plane substantially between said distributor magazine and said magazine channels, a holder for the type collected arranged below the lower ends of the magazine channels, and a type collector for carrying type from the magazine channels to the holder and movable in a plane substantially between the magazine channels and said holder.

84. A keyboard machine for setting and distributing type comprising in combination with the keys, a series of stops, a distributor, a type releasing device carried by the distributor, said device being adapted to be operated by contact with one of said stops, and keyboard controlled means for bringing one of the stops in position to operate the releasing device carried by the distributor.

85. In a type distributing machine, the combination of a plurality of upright stationary type magazine channels, a type carrier movable into operative relation to the upper ends of said channels to drop type therein, means for placing the type carrier into operative relation to the upper ends of said channels, keyboard-actuated means for moving said carrier to and stopping said

carrier at a channel, and means on said carrier which are actuated by said stopping means to release the type.

86. The combination of a keyboard comprising a plurality of keys, a plurality of type magazine channels, a carrier movable into operative relation to the channels, means actuated by said keys for stopping said carrier in operative relation to a magazine channel, and means for permitting the

operation of one or another of said stops by a key.

Signed at Buffalo in the county of Erie and State of New York this 28th day of June A. D. 1913.

ALLISON M. MACFARLAND.
